(57) **CLAIM**

The ornamental design for a shoulder and closure for a tube, as shown and described.

DESCRIPTION

FIG. 1 is a perspective view of our design of the shoulder and closure for a tube.

FIG. 2 is a right side elevation view thereof.

FIG. 3 is a rear elevation view thereof.

FIG. 4 is a left side elevation view thereof.

FIG. 5 is a front elevation view thereof.

FIG. 6 is a top plan view thereof.

FIG. 7 is a bottom plan view thereof; and,

FIG. 8 is a perspective view thereof with the closure opened. The broken line drawing of a tube is for illustrative purposes only and forms no part of the claimed design.
